(57) CLAIM

The ornamental design for a bedwetting alarm as shown and described.

DESCRIPTION

FIG. 1 is a front, right and top perspective view of a bedwetting alarm, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the bedwetting alarm that form no part of the claimed design.

The break lines in the drawings indicate that the appearance of any portion of the bedwetting alarm between the break lines forms no part of the claimed design.
